UNITED STATES PATENT OFFICE

144,193

DESIGN FOR A COMBINATION VANITY AND INCIDENTAL CASE OR SIMILAR ARTICLE

Spiros Katopodis, Boston, Mass.

Application May 30, 1945, Serial No. 119,807

Term of patent 7 years

(Cl. D86—10)

To all whom it may concern:

Be it known that I, Spiros Katopodis, a citizen of the United States, residing at Boston, in the county of Suffolk, in the Commonwealth of Massachusetts, have invented a new, original, and ornamental Design for Combination Vanity and Incidental Case or Similar Article, of which the following is a specification, reference being had to the accompanying drawings, forming a part thereof, in which:

Figure 1 is a front elevational view of a combination vanity and incidental case showing my new design in closed position.

Figure 2 is a side elevational view of said case.

Figure 3 is a perspective view of said case with the covers partly open.

Figure 4 is a top plan view thereof.

Figure 5 is a perspective view of said case with the outside front cover open and two inner compartment lids open, and Figure 6 is a perspective view thereof with the outside rear cover open and an inner compartment lid open.

I claim:

The ornamental design for a combination vanity and incidental case or similar article, substantially as shown.

SPIROS KATOPODIS.
